UNITED STATES PATENT OFFICE.

JOHN N. WHITEHOUSE, OF NEW YORK, N. Y.

DESIGN FOR LAMP STAND.

Application filed May 19, 1923. Serial No. 6,225. Term of patent 3½ years.

To all whom it may concern:

Be it known that I, JOHN N. WHITEHOUSE, a citizen of the United States, residing in New York, in the county of New York and State of New York, have invented a new, original, and ornamental Design for Lamp Stands (Case 2), of which the following is a specification, reference being had to the accompanying drawing, forming part thereof.

In the drawings, the figure is a front view, showing my new design.

I claim:

The ornamental design for lamp stand as shown.

JOHN N. WHITEHOUSE.
